[57] CLAIM

The ornamental design for a downrigger control board, as shown and described.

DESCRIPTION

FIG. 1 is a side elevational view of a downrigger control board showing my new design;

FIG. 2 is a top plan view thereof;

FIG. 3 is a front elevation view thereof;

FIG. 4 is a front perspective view thereof;

FIG. 5 is a side elevational view of a second embodiment of the downrigger control board;

FIG. 6 is a top plan view of FIG. 5;

FIG. 7 is a front perspective view of FIG. 5;

FIG. 8 is a front elevational view of FIG. 5; and

FIG. 9 is a bottom plan view of FIG. 5.
